NAYA BRANDT, OF NEW YORK, N. Y.

SANITARY APRON

Application filed January 7, 1928. Serial No. 245,191.

An important object of the present invention is to provide improved means for attaching a sanitary apron or shield to a garment.

5 Another object of the invention is to provide improved attaching means for a sanitary apron, which will effectually prevent accidental detachment of the apron from the garment to which it is applied, avoid discomfort to the wearer, and provide for the ready disconnection of the apron and garment for separate cleaning or laundering.

10 Another object of the invention is to provide a sanitary apron unit for attachment to a garment, comprising an attaching band adapted to be stitched to the garment, and an apron detachably held to said band by lacing means. When the unit is applied to a garment the band remains permanently attached thereto while the apron may be readily unlaced and removed. The lacing means provides maximum security against accidental detachment of the apron, and its flexibility prevents discomfort to the wearer such as 25 would be caused by buttons or snap fastenings.

In the drawings, Fig. 1 is a front view of an undergarment partly broken away to disclose my improved apron unit applied to the inner side of the back portion of the garment;

Fig. 2 an enlarged detail section taken on the line 2—2 of Fig. 1;

Fig. 3 a detail section taken on the line 3—3 of Fig. 1;

Fig. 4 a fragmentary view showing the apron unlaced from its supporting band; and

Fig. 5 a face view of the apron unit per se.

My invention is particularly designed for application to a garment 1 of the slip or camisole type. However, it may be used in connection with other forms of garments. The apron unit includes an attaching band 2 formed of a strip of freely flexible fabric. This strip is folded longitudinally to double its thickness, and between its free longitudinal edges a narrow edge strip 3 is secured. The latter extends substantially the length of the band 2 and carries a series of small loops 4. These loops depend from the band 2

and are equally spaced along the length of the strip 3. A sanitary apron 5 formed of rubberized silk or other suitable waterproof material is supported by the attaching band 2. Secured to the upper edge of the apron is a freely flexible fabric strip 6. The latter is folded to double its thickness and the apron is stitched to it as at 7 between the folds. This strip is substantially co-extensive in length with the supporting band 2 and its upper folded edge is straight. Its lower edges, however, curve downwardly to increase the width of its medial portion. The width of the apron is less than the length of the strip so that the ends of the latter extend beyond the side edges of the apron. Secured along the upper edge of the strip 6 is a narrow edge strip 8 which carries a series of upwardly extending loops 9. These loops are equally spaced and similar to the depending loops 4 and are disposed between the latter. A lacing strand 10 is threaded through the loops of both series. This strand is securely attached at one end to the apron strip 6 as indicated at 11. At its opposite end it is tied in a bow 12 so that it may be readily united and withdrawn from the loops when desired. The strand, the loops and the edge strips 3 and 8 are all formed of slender silk braid, so that the connection between the apron and the supporting strip 2 is of slight bulk and is freely flexible.

Preferably the apron unit, comprising the apron, the supporting band 2 and the lacing means, will be all made up and assembled prior to its application to a garment. It may form an article of commerce separate from the garment or it may be attached to the latter and sold with it. To apply the article to the garment 1 the apron supporting band 2 is placed within the garment at a suitable position upon the back thereof and permanently secured in place by longitudinal stitching 13. The ends of the band are also turned under and secured to the garment by transverse stitching 14. The apron then depends from the band, within the garment, in a position to shield the latter and also the outer garment. The lacing effectually prevents accidental detachment of the apron or any part

thereof under strain and the wearer is therefore relieved of anxiety. If a downward pull is exerted upon the apron at any point the lacing means will yield and distribute the strains. There are a large number of the 5 safeguard the apron, the lacing means, the attaching band and the garment from rupture when the apron is subjected to pulling strains. There are a large number of the 10 small loops 4 and 9 and even if the lacing strand 10 were to break or become untied no material sagging or detachment of the apron would result. Also by the provision of such 15 connecting means I avoid the use of buttons, snap fasteners or the like which are hard and cause discomfort, in addition to being unreliable when subjected to strain. The lacing means is soft and freely flexible; is arranged between the lower edge of the band 2 and the upper edge of the band 6 and is of negligible bulk so that it causes no discomfort whatever and does not add to the thickness of the garment. When it is desired to 20 remove the apron the bow 12 is untied and the lacing strand 10 is withdrawn from the loops. The apron is then released from the supporting band 2 while the latter remains attached to the garment.

What I claim is:

1. The combination of a garment; a sanitary apron; a relatively large number of freely flexible depending loops attached to the garment and arranged in a row around it; a corresponding row of companion flexible 25 loops carried by the apron and extending above the upper edge thereof; and a freely flexible lacing strand trained through the loops of both rows and detachably held against withdrawal, whereby the apron is 30 supported by freely flexible lacing means designed to permit a yield and a distribution of strain therealong when the apron is subjected to pulling strains, and the apron, lacing means and garment are safeguarded from 35 rupture.

2. A sanitary apron unit comprising an apron; a flexible attaching band extending along the upper edge of the apron and adapted to be stitched to a garment; a relatively 40 large number of flexible depending loops carried by the band and arranged in a row therealong; a relatively large number of flexible loops carried by the apron and extending in a corresponding row along the upper edge 45 of the apron; and a lacing strand trained through the loops of both rows to detachably hold the apron to the attaching band, said strand and loops permitting a yield and a distribution of strain therealong when the 50 apron is pulled.

3. A sanitary apron unit comprising an apron; a freely flexible attaching band extending along the upper edge of the apron and adapted to be stitched to a garment; a 55 relatively large number of freely flexible

loops carried by the band, arranged in a row, and extending below the lower edge of the band; a corresponding row of flexible companion loops carried by the apron and extending above the upper edge thereof; and a flexible lacing strand trained through the loops of both rows between the band and the apron and detachably held against withdrawal, whereby the band and apron are connected by freely flexible lacing means disposed between the band and apron, all will lie substantially flush when the band is attached to a garment, and the lacing means will permit a yield and a distribution of strain therealong when the apron is pulled. 70

4. The combination of a garment; a sanitary apron; a freely flexible apron-supporting band extending transversely around the garment and stitched thereto along its length; a relatively large number of freely flexible loops carried by the band, arranged in a row and extending below the lower edge of the band; a corresponding row of flexible companion loops carried by the apron and extending above the upper edge thereof; and a freely flexible lacing strand trained through the loops of both rows between the band and the apron and detachably held against withdrawal, whereby the band and the apron are connected by freely flexible lacing means disposed between the band and apron, all being substantially flush, and the lacing means will permit a yield and a distribution of strain therealong when the apron is pulled. 75

In testimony whereof I hereunto affix my signature.
